UNITED STATES PATENT OFFICE.

WILLIAM P. STRICKLAND, OF CHICAGO, ILLINOIS.

BOARD-FILLING MACHINE.

Application filed October 8, 1923. Serial No. 667,348.

To all whom it may concern:

Be it known that I, WILLIAM P. STRICKLAND, a citizen of the United States, residing at Chicago, in the county of Cook and State 5 of Illinois, have invented a new and useful Improvement in Board-Filling Machines, of which the following is a specification.

My invention relates to certain new and useful improvements in board-filling machines, and is fully described and explained in the specification and shown in the accompanying drawings, in which—

Figure 1 is a view in front elevation of one form of machine constructed in accordance with my invention and showing the parts thereof in the position they assume during the charging of the strip-magazine with indicia-bearing strips which may be of paper and are to be severed into sections 20 and thereupon introduced into the rows of holes in the board to be filled. Figure 2 is a view in side elevation of the machine. Figure 3 is a view in front elevation of the central portion of the machine, with certain parts shown in section, this view showing the position the parts assume after portions of the strips in the magazine have been fed therethrough, severed and introduced into rows of holes in the board. Figure 4 is a plan, sectional, view of the machine, the section being taken at the irregular line 4—4 on Fig. 6 and viewed in the direction of the arrows. Figure 5 is a bottom plan sectional view taken at the line 5 on Fig. 3 and viewed in the direction of the arrows. Figure 6 is a section taken at the irregular line 6—6 on Fig. 4 and viewed in the direction of the arrows. Figure 7 is a section taken at the irregular line 7—7 on Fig. 4 and viewed in the direction of the arrows. Figure 7^a is an enlarged detail like Fig. 7 of certain of the parts therein shown. Figure 8 is a section taken at the line 8—8 on Fig. 4 and viewed in the direction of the arrows. Figure 8^a is an enlarged view, like Fig. 8, of a portion of the board-feeding and centering mechanism therein shown. Figure 9 is a section taken at the line 9—9 on Fig. 8 and viewed in the direction of the arrows. Figures 10 to 14 inclusive are sections taken at the lines 10, 11, 12, 13 and 14, respectively, on Fig. 4 and viewed in the direction of the respective arrows. Figure 15 is a section taken at the line 15—15 on Fig. 5 and viewed in the direction of the arrows.

Figure 15^a is an end view of one of the similar crimped strip-sections. Figure 16 is an end view of a strip-receiving and compressing device for receiving the strips 60 preparatory to their introduction into the strip magazine of the machine. Figures 17 and 18 are face views of the two co-operating rib-equipped members comprising the device of Fig. 16. Figure 19 is an enlarged 65 section taken at the line 19—19 on Fig. 16 and viewed in the direction of the arrows. Figure 20 is a view, in side elevation, with certain parts broken away, of a modification of the machine of the preceding figures. 70 Figure 21 is a view in front elevation of the machine in Fig. 20. Figure 22 is an enlarged view, in side elevation, certain parts being sectioned, of a portion of the machine shown in Fig. 20. Figure 23 is 75 a broken, enlarged, sectional view taken at the line 23—23 on Fig. 24 and viewed in the direction of the arrows. Figure 24 is a fragmentary view, in side elevation, of certain of the parts shown in Fig. 22, the 80 parts being shown in a different position; and Figure 25, an enlarged fragmentary view taken from the front of the machine and viewing the parts shown in the direction of the arrow 25 in Fig. 22. 85

As a preface to the following description of the machine and its operation, it may be stated that the boards to be charged, one such board being represented at 35, contain, in their upper surfaces, in accordance with 90 common practice, series of parallel rows of holes 36 and in their lower surfaces series of parallel rows of holes 36^a, the latter registering respectively with the former, though it will be understood that the 95 machine may operate on boards wherein the holes to be charged extend entirely through the board.

Referring to the construction of machine illustrated in Figs. 1 to 19 inclusive, the frame of the machine is shown as formed of a table top portion 30 supported on legs 31, the legs 31 at opposite sides of the machine being braced by side bars 32 to which a plate 33 is connected by U-bolts 34. In 100 the particular construction shown the board 35 is supported on the table top 30 and is moved lengthwise thereof, to present its rows of holes 36 successively to the mechanism which charges into these holes the 105 indicia-bearing strip sections, the movement of the board as stated, being a step-by-step 110

movement and produced by mechanism comprising a shaft 37 (Figs. 1, 2, 5, 7 and 8) journaled in brackets 38 depending from the under side of the table top 30 and carrying, rigid therewith, two drums 39 spaced apart and extending part way upwardly through slots 40 in the top 30, the uppermost peripheral surfaces of these drums preferably extending substantially flush with the upper surface of the top 30. Each of the drums 39 is open at its opposite ends, as shown in Fig. 8, and each is provided in its circumferential side wall, adjacent its opposite edges, with circumferential series 15 of apertures 41 in which radially-extending pins 42 are located, these pins, which are slidable radially in the openings 41, being provided at their inner ends with heads 43 which, in the position of the pins shown in Fig. 8, abut the inner surfaces of the drums in which they are slidable, the pins 42 in this position extending radially beyond the circumference of the drums, the pins 42 of each series thereof being equidistantly spaced apart a distance equal to the distance between adjacent rows of the holes 36—36^a, and the several circumferential rows of these pins being so positioned that they will register with certain of the holes 36^a in each row thereof, whereby the board 35 is adapted to be moved along the table top through the medium of the pins 42 entering the apertures therein, when the drums 39 are rotated as hereinafter described, it being noted, in this connection, that by providing mechanism for feeding the board, which operates to effect the feed by extending into the holes 36^a in registration with the holes 36 for receiving the indicia-bearing strip sections the feeding of the board, to cause the holes 36 therein to be brought into the desired registration with the mechanism which feeds the strip sections into these holes and hereafter described, is accurately performed. The pins 42 are normally held in the position shown in Fig. 8, by means of springs 44, shown as leaf springs, which are secured at one end to the drum, as indicated at 45, and engage at 40 their opposite ends with heads 43 of the pins with which they cooperate. The pins 42 are spring-pressed in order that the ones thereof which are at the upper portions of the drum 39 when the board is introduced into the machine before filling of the holes 36 therein begins and also after the last row of holes in the board have been filled (the board at its opposite ends having imperforate portions) may recede under the force 45 exerted against them by the board. It is, however, desirable, when the pins 42 extend into holes 36^a in the board after feeding the latter, that at least a portion of these particular pins be held rigid, and to this end I provide a pair of levers 46 of general bell-

crank form which are pivoted at their angles, as indicated at 47, on a wall of the slot 40 (Figs. 7 and 8), these levers extending crosswise of the machine and each being provided at its arm 48 with an upwardly-extending stud 49 having a cone-shaped upper end adapted to enter a similarly shaped recess 50 in the under side of the head 43, it being understood that all of the heads 43 of the two intermediate circumferential rows of pins 42 are provided with the recesses referred to. The other, depending, arms 51 of the levers 46 are connected together by a coil spring 52 tending to rock these levers in opposite directions to lower 50 their arms 48. Co-operating with the levers 46, at the arms 48 thereof, is a wedge-bar 53 which extends lengthwise of the machine and is guidingly supported to reciprocate between the arms 51 adjacent to which latter the wedge surfaces 54 of the bar 53 extend. In the position of the bar 53 shown in Fig. 5, this bar has been moved to the right to extreme position, in which position the levers 46 engage at their studs 49 with the heads 43 and rigidly hold the pins carried thereby against downward displacement, it being understood that the only pins which are thus rigidly held are the uppermost ones of the intermediate longitudinal series thereof. The wedge-bar 53 carries a roller 55 mounted on a stud 56 carried by this bar, this roller co-operating with a cam 57 secured to a shaft 58 journaled in bearings 59 depending from the table top 30 and driven as hereinafter described, the rear end of the rod 53 being slotted, as indicated at 60, through which slot the shaft 58 extends. The spring 52 tends to move the rod 53 to the left in Fig. 5, thereby holding the roller 55 against the periphery of the cam 57, it being understood that the rod 53 will be held in the position shown in Fig. 5 at all times, except when the depressed portion 61 of the cam 57 opposes the roller 55 and 65 when this occurs, the rod 53 shifts to the left in Fig. 5 and permits the spring 52 to rock the levers 46 to a position in which the studs 49 of the latter are lowered to a position in which they do not interfere with the depressing of the pins 42 directly above them. It may be here stated that the parts of the machine are so constructed and arranged that the depressed portion 61 of the cam 57 opposes the roller 55, and the bell-crank 46 consequently are withdrawn from pin-engaging position, during the rotation of the drums 39, by the intermittently-operating mechanism hereinafter described, and, furthermore, that at the end of each 70 cycle of operations hereinafter described and at which time the machine automatically stops, the depressed portion 61 of the cam 57 opposes the roller 55 thereby permitting a board 35 to be introduced into place in 75 130

the machine for filling, or the filled board, to be withdrawn from the machine.

In the movement of the levers 46 into engagement, at their tapered studs 49, with the conical recesses 50 in the pins 42, a centering action on the drums occurs, the drums in this centering action being free to slightly rotate, and thus accurate positioning of the drums relative to the mechanism, hereinafter described, for introducing the strip sections into the board, is effected.

Co-operating with the board 35, and serving as a means for yieldingly pressing the latter downwardly and firmly against the top 30, is a roller 62 mounted on a shaft 63 rotatably supported at its ends in rearwardly-extending arms 64 pivotally connected at 65 with lugs 66 depending from the base member 67 of a housing 68 supporting the top 30 at posts, represented at 69, the arms 64 being connected together, between their ends, by a cross-bar 70 to which the head 71 on the lower end of a rod 72 is pivotally connected. The rod 72 extends upwardly into the housing 68 through an opening 73 in the base 67 thereof, and is surrounded by a coil spring 74 which bears at its lower end against the head 71 and at its upper end against a collar 75 surrounding the rod 72 and movable up and down thereon, the collar 75 abutting, under the tension of the spring 74, the under side of a stud 76 rigidly secured to a standard 77 rising from the base plate 67, the parts just described being so proportioned and arranged that when the board 35 is interposed between the roller 62 and the top 30, the spring 74 will be under tension and cause this roller to bear with the desired force downwardly against the board. The roller 62 is adapted to be raised, against the action of the spring 74, at the will of the operator, through the medium of a shaft 78 journaled in the sides of the housing 68, this shaft being provided at its outer end with a hand lever 79 and between its ends with a cam 80 which extends directly beneath, and in engagement with, a spring strip 81 mounted at one end on a shaft 82 journaled in the housing 68 to rotate therein, the other, free, end of the strip 81 containing an aperture through which the upper end of the rod 72 extends, the portion of this rod which extends above the strip 81 being provided with nuts forming a shoulder extending above the strip. When the lever 79 (Fig. 2) is rotated in counter-clockwise direction therein, the cam 80 operates to lift the free end of the strip 81 which, in engaging with the shoulder 83, raises the rod 72, and consequently the roller 62 against the action of the spring 74.

The feeding drums 39 are rotated intermittently to cause the board 35 to feed through the machine by a step-by-step

motion, by means of the driving mechanism of which the following is a description: One end of the shaft 37 is provided with a ratchet 84 rigid thereon (Fig. 15) which cooperates with a pawl 85 shown as in the form of a bent lever pivotally supported between its ends, as indicated at 86, on a reciprocating rod 87 and having a tooth 88 cooperating with the ratchet 84, the rear end of the pawl lever being connected with a spring 85^a attached to the machine and operating to yieldingly hold this pawl in engagement with the ratchet 84. The pawl 85 is caused to rotate the ratchet 84 a distance of one tooth, in counter-clockwise direction in Fig. 15, each time the rod 87 makes a complete reciprocation. The rod 87 contains in its forward end a slot 89 at which it surrounds the shaft 37, the latter forming a guide for the rod 87. The rear end of the rod 87 is slotted, as indicated at 90, at which it surrounds a shaft 91 journaled in bearings depending from the under side of the top 30 and driven as hereinafter described, this shaft having rigid thereon a cam disk 92 and a collar 92^a, the lower portion of the cam surface of the disk 92 being represented at 93. The cam-disk 92 cooperates with a roller 94 journaled on a stud 95 carried by the rod 87, a coil spring 96 connected at one end, as indicated at 97, to the top 30 and at its upper end, as indicated at 98, to the rod 87 operating to hold the roller 94 at all times in engagement with the peripheral cam surface of the cam 92. The collar 92^a is provided with a radially projecting lug 92^b and the rear end of the pawl-lever 85 bears upwardly against the periphery of the collar 92^a. It will be understood from the foregoing that in the rotation of the cam 92 the rod 87 will be given an intermittent reciprocating movement and in each complete reciprocation will partially rotate the ratchet 84 and thereby actuate the board-feeding drums 39.

Means are provided for arresting the feeding of the board by the drums 39, at the will of the operator, these means comprising a lever 99 fulcrumed at 100 on the top portion 30 of the frame, one end of this lever, represented at 101, being accessible for operation by the operator and the other end thereof being provided with a pin 102 which extends under the tooth portion 88 of the pawl 85 and, when the lever 99 is rocked in clockwise direction in Fig. 15, rocks the pawl out of engagement with the ratchet 84. The machine is provided with means whereby the step-by-step feeding of the board by the mechanism described may be regulated to vary the length of movement of the board with each feeding operation, to the end that the board may be fed a distance equal to the distance between the centers of adjacent rows of the holes therein to be filled or twice or three times the distance between centers of

adjacent holes in the board to be filled whereby the holes 36 in the board may be filled, by the mechanism hereinafter referred to, in regular order, or by skipping one or more rows with each feeding operation as desired. The means shown for this purpose comprise a disk 103 provided on its periphery with a series of step surfaces 104 and 105, the periphery of this disc being 10 opposed by a lug 106 projecting rearwardly from the reciprocating rod 87. The periphery of the disc 103 controls the extent of rearward movement of the rod 87 under the action of the spring 96. The disc 103 is rotatably supported on the frame of the machine and is adapted to be moved into a position in which either the circular portion of its periphery or either of the step surfaces 104 and 105 are in direct line with the lug 106. When the circular periphery of this disc is in line with this lug, the rod 87, when the depressed surface 93 of the cam opposes the roller 94, is free to move to the left in Fig. 15, under the action of the 25 spring 96, a distance sufficient to cause the pawl 85 to be preliminarily positioned, relative to the ratchet 84, for rotating the latter a distance of one tooth. In this adjustment the board is fed a distance equal to the distance between centers of adjacent holes in 30 the board to be filled. When the disk 103 is rotated to a position in which the step surface 104 is in line with the lug 106, the rod 87 is free to move to the left in Fig. 15 a 35 distance sufficient to cause the ratchet to be rotated a distance of two teeth thereof when the rod 87 is again forced to the right in Fig. 15, thereby to feed the board a distance equal to twice the distance between adjacent 40 rows of holes to be filled or, in other words, skipping each alternate row of holes; and when the disc 103 is rotated to cause the step surface 105 to be in line with the lug 106 the bar 87 is permitted to move to the left 45 in Fig. 15 sufficiently far to position it for rotating the ratchet 84 a distance of three teeth thereof for causing the board to feed a distance equal to three times the distance between adjacent rows of holes therein, thereby causing the skipping of two rows with 50 each board-feeding operation.

Referring now to the mechanism for inserting the strip-sections into the holes 36 in the board 35; the side walls of the housing 68 are provided with forwardly-projecting arms 107 containing upwardly-opening slots 108 adapted to receive the laterally-extending studs 109 on a removable and replaceable magazine 110 for the strips to be severed into sections and introduced into the holes 36 in the board. The magazine 110 is formed of a frame 111 provided with a back plate 112 and a horizontal series of vertically-extending ribs 113 equidistantly spaced apart and forming grooves open at

their upper and lower ends for receiving the indicia-bearing strips, the front side of the magazine 110 being provided with a plate 114 of transparent material, as, for example, glass, which is preferably slightly spaced from ribs 113 and forms the front wall of the pluralities of strip-receiving grooves referred to, this plate being shown as held in place by clips 115 on the frame 111. The magazine 110 is provided, below the studs 109, with laterally-extending studs 116 adapted to be releasably engaged by rock levers 117 mounted between their ends on a shaft 118 journaled in the housing 68. Coil springs 119 are interposed between the rear ends of the levers 117 and the base plate of the housing 68 and tend to rock these levers downwardly at their outer ends. Journaled in the housing 68, in a plane above the levers 117, is a shaft 120 provided with a handle 120^a, this shaft carrying cam lugs 120^b disposed directly above the rear ends of the levers 117 and operating when the shaft 120 is rotated to rock the levers 117 against the resistance of the springs 119, to a position in which these levers are disengaged from the studs 109 when it is desired to remove the magazine from the machine. The magazine 110 is provided with shearing mechanism for shearing the strips therein, into sections, when the strips are advanced through the magazine, as hereinafter described, to a certain position therein, the shearing mechanism referred to comprising a shearing bar 121 flatwise opposing the under side of a cross-bar 122 provided across the lower end of the magazine and containing a horizontal series of apertures 123 extending entirely therethrough and in alignment with the channels provided between the ribs 113, these apertures flaring slightly upwardly. The shearing bar 121 which is located adjacent the forward edge portion of the cross-bar 122, contains at its opposite end portions, openings 124 into which depending crank-pins 125 provided on disks 126, extend, the disks 126 being rotatably confined in openings 127 in the cross-bar 122, and fixed on the lower ends of shafts 128 journaled in the side portions 111 of the magazine, the crank-pins 125 which, when the shafts 128 are rotated, operate the shearing blade 121 as hereinafter described, being preferably disposed in different angular positions, as shown. The upper ends of the shafts 128 are provided with discs 129 having laterally-extending arms 130 which, under the action of coil springs 131 surrounding the rods 128 and interposed between shoulders on the side portions 111 of the magazine 110, and the discs 129, tend to bear rearwardly against the forward ends of push bars 132 slidably mounted in the front wall 133 of the housing 68, the rear ends of these rods being slotted, as indicated 130

at 134, through which slots a shaft 135, journaled in the housing 68, extends, this shaft being driven as hereinafter described and carrying cams 136 and 137 into the path of movement of which rollers 136^a and 137^a, respectively, on the push rods 132 extend, these rods being connected with the forward end of coil springs 138 fixed at their rear ends, as indicated at 139, to the housing 68, 5 it being noted that the cam 137 is narrower than the cam 136 and that it acts against the roller 137^a after the cam 136 begins its action against the roller 136^a and ceases to act against roller 137^a before the cam 136 ceases 10 to act against the roller 136^a.

In the operation of the machine each complete rotation of the shaft 135 causes the pusher rods 132 to be reciprocated thereby partially rotating the disks 126. The arrangement of the crank-pins 125 and the position of the cams 136 and 137 as stated, 20 causes the shearing blade 121 to be simultaneously reciprocated and moved back and forth at an angle to the plane of its reciprocation, one end of the shearing bar traveling in these movements in advance of the opposite end thereof and producing a highly efficient shearing action on the strips.

30 The machine also involves the use of feed rollers preferably of metal, located at opposite sides of the strips to be fed, adjacent their lower ends, these rollers being represented at 140 and 141. The lower edge portions of the plates 112 and 114 are cut away, as represented at 142 and 143, to permit these rollers to yieldingly grip between them the strips to be fed. The roller 140 is provided at its opposite 35 ends with stub shafts 144 at which it is journaled in the lower ends of brackets 145 located at opposite sides of the magazine 110 and pivotally supported on the latter, as indicated at 146. The roller 141 is provided at its opposite ends with stub shafts 147 journaled in the lower ends of brackets 148 provided at opposite sides of the magazine 110 to oppose the brackets 145, the brackets 148 being pivoted on the magazine, 40 as represented at 149. The brackets 145 and 148 are provided with upwardly-extending arms 150 and 151, respectively, between pairs of which coil springs 152 and 153 are interposed, these springs tending 45 to rock the brackets 145 and 148 in a direction to move the rollers 140 and 141 toward each other. Each of the springs 153 surrounds a rod 154 located between the pairs of brackets and relative to which the bracket 148 is movable, the outer ends of 50 these rods being provided with cam levers 155 pivoted thereto and bearing against the forward faces of the arms 151, these levers providing a means whereby the brackets 150 and 151 may be swung in a direction to

move the rollers 140 and 141 in a direction away from each other. The rollers 140 and 141 are positively intermittently driven in opposite directions to cause them to perform the feeding function, by means of gears 156 and 157 secured to the stub shafts 144 and 147 at one end of the magazine, these gears meshing, respectively, with gears 158 and 159 journaled on studs carried by the brackets 145 and 148 at the right hand side 70 of Fig. 3. The gear 158 is rigid with the internal member of a clutch device represented generally at 160, this gear meshing with the gears 156 and 159 whereby rotation of the internal clutch member referred to, in clockwise direction in Fig. 10 operates to rotate the feed roller 140 in clockwise direction in Fig. 10 and the feed roller 141 in counter-clockwise direction in this figure. The clutch device 160 also involves 75 an internal clutch element 161 and clutch elements interposed therebetween and between the internal clutch member whereby rotation of the external clutch member 160 in clockwise direction in Fig. 10 rotates the gear 158 in the direction above referred to, but has no action on this gear when the member 160 is rotated in counter-clockwise direction by the action of the coil spring 162, in this figure. The clutch mechanism 80 shown is of a type well known generally in the arts for effecting intermittent rotary movement of shafts, and detailed description thereof is therefore not necessary. The external clutch member 160 is provided with 85 a radially-extending arm 163 provided with a roller 164 which bears, under the action of the spring 162, against the forward, adjustable, end portion 165 of a pusher bar 166 slidably mounted in guides on the housing 68, a coil spring 167 surrounding the bar 166 and bearing at opposite ends against the wall 133 of the housing 68 and a stoppin 90 168 on the bar 166, yieldingly forcing this bar to the left in Fig. 10. The mechanism for intermittently actuating the bar 166 to produce intermittent rotation of the feed rollers comprises a lever 169 pivotally supported at its upper end on the housing 68, as indicated at 170, this lever being pivotally connected between its ends, as indicated at 171, with the forward end of a link 172, the rear end of which is pivotally connected, at 173, with the lower end of a lever 174 journaled on a shaft 175 carried by the housing 68. Rigid with the lever 174 is a lever 176 carrying a roller 177 at its lower end, which extends into the path of a cam 178 fixed on the shaft 135, this cam operating to intermittently rock the lever mechanism described in a direction for forcing the pusher bar 159 to the right in Fig. 10 and turning the clutch element 160 in clockwise direction in this figure, 100 against the action of the springs 162 and 105 110 115 120 125 130

167, the parts thus actuated by the cam 178 returning to normal position upon the disengagement of the cam 178 from the roller 177.

5 The strips charged into the magazine, preferably as hereinafter described, are intermittently fed downwardly through the magazine, by intermittently-actuated pusher rods, represented at 179, which extend into 10 the channels in which the strips are located. The pusher rods 179 are dependently supported on a cross-bar 180 and are engaged between their ends by a spacing member 181. The bar 180 is carried on the lower ends 15 of arms 182 secured to a cross-bar 183 provided at its ends with sleeves 184 which surround, and are slidable up and down on, upwardly-extending guide-rods 185 secured to, and rising from, the housing 68, the upper ends 20 of these guide rods being connected together by a cross-member 186. The cross-bar 183 is provided with depending rods 187 which extend slidably through openings in the ends of a cross-member 188 provided 25 with rearwardly-extending sleeves 189 which surround, and are slidable up and down on, the guide rods 185, the rods 187 being provided at their lower ends, which extend beneath the bar 188, with stops 190, 30 shown as in the form of nuts, which limit the movement of the sleeves 184 and 189 in a direction away from each other, while permitting the upper sleeves 184 and the parts rigidly connected therewith, to descend relative to the sleeves 189 in the operation of the machine as hereinafter described. The bar 188 is also provided with depending brackets 188^a connected at their lower ends with a plate 188^b so positioned 35 that it extends directly above the magazine 110, and rests upon the top of the latter during the operation of the machine as hereinafter described. The plate 188^b forms a guide for the rods 179 holding 40 these rods in properly aligned position, and to this end is slotted, as represented at 188^c. A handle 190 is connected with the arms 182, being provided for manually raising and lowering the frame just referred to, to 45 raise and lower the pusher rods 179 as desired. Means are provided for substantially counterbalancing the frame just referred to, together with the parts carried thereby, these means comprising a cable 191 50 connected at one end with the cross-member 183 and thence extending upwardly over pulleys 192 and 193 journaled on the cross-member 186, the lower, opposite, end of the cable 191 carrying a weight 194 sufficient 55 to effect the substantial counterbalancing referred to.

The means shown for effecting the intermittent downward feeding of the pusher rods 179 comprise a rack 195 provided on 60 a bar 196 secured at its upper end to the

cross-member 183 by means of brackets 197, this rack cooperating with a pawl device represented generally at 198 and intermittently reciprocated up and down by means hereinafter described. The pawl proper of the pawl device 198 is represented at 199 and is provided on the upper end of a pawl-actuating rod 201 pivotally connected at its lower end, as represented at 202, to the forward end of a lever 203 pivotally connected, 70 between its ends with a shaft 204 mounted in standards rising from the base 67 of the housing 68, a spring 201^a operating to yieldingly hold the pawl 199 in engagement with the teeth of the rack 195. The rear end of the lever 203 is provided with a roller 205 which is held against the periphery of a cam 206 on the shaft 135, by a coil spring 207 secured at its lower end to the base 67 and at its upper end to the rear end of the lever 203. The rack bar 196 is slidable up and down in a channel 208 rising from, and rigidly secured to, the housing 68, the pawl 199 and its operating rod 201 being likewise movable in this channel. The pawl proper 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 pivotedly supported, as indicated at 218, to the rear ends of bars 219 pivotally connected at their forward ends, as represented at 220, to depending lugs 221 on the base 5 member 67 of the housing 68, the engagement of the pivoting studs 218 with the bars 219 being at slots 222 in the rear ends of the bars 219. The carrier member 216 is provided, for the purpose of receiving 10 the strip sections referred to, with a series of square openings 223 from the sides of each of which depend four spring fingers 224 which are grouped about the four sides of these openings and which normally assume 15 the inward deflected, tapering, position, as illustrated of those shown in Fig. 7^a, the parts being so constructed and arranged that when the carrier member 216 is in forwardmost position (Fig. 7) the openings 223 will 20 register with the openings 123 in the bottom of the magazine, and when the member 216 is in its extreme rear position the openings 223 will register with plunger rods 225 supported, and operated, as hereinafter 25 described, and positioned directly above the line of holes 36, in the board, to be filled, in which position the carrier member 216 extends below the position shown in Fig. 7 and the lower ends of the spring fingers 224 project 30 into the upper ends of the holes 36 to be filled. The member 216 is preferably formed of a plate member 226 in which the openings 223 are provided, this plate member being provided with a downwardly-opening 35 channel 227 extending lengthwise thereof, and a presser bar 228 located in this channel and secured to the plate 226 in a manner to permit the plate 226 and the bar 228 to have relative up and down movement, as by means of the studs 229, these 40 studs being surrounded by springs 230 which operate to yieldingly force apart the plate 226 and the bar 228. The bar 228 is adapted to press downwardly against 45 the board 35 when the carrier member 216, of which it is a part, is moved to rearwardmost position and extends at its fingers 224 into the holes 36 to be filled, the 50 springs 230 in this position of the parts being under tension and operating to press the bar 228 against the upper surface of the board 35 with the desired pressure for insuring against slippage of the board. The 55 mechanism for operating the carrier member 216 into and out of the positions above referred to, comprises means for reciprocating and raising and lowering this member, these means comprising levers 231 pivotally supported at their upper ends as indicated 60 at 232 on the housing 68 and pivotally connected at their lower ends, as indicated at 233, with the bars 217, between the ends of the latter. The levers 231 are pivotally connected, at 234, with the forward ends of 65 links 235 containing elongated slots 236 at their rear ends at which they surround the shaft 135, the links 235 being provided between their ends with rollers 237 which press at all times, under the action of a spring 239, against the peripheries of cams 238 70 rigidly secured to the shaft 135, the spring 239 tending to shift the carrier member 216 to the right in Fig. 7, or, in other words, rearwardly. The raising and lowering of the carrier member 216 is effected through 75 the medium of a link 240 pivotally connected, as indicated at 241, to the forwardly-extending lug 242 of a bracket 243 secured to a cross-member 244 connecting the rods 219 together at their rear ends. The upper 80 end of the link 240 carries a pivoting stud 245 pivotally connecting to this link a spring-abutment member 246 provided with outwardly-extending arms 247 between 85 which and the base portion 67 of the housing 68, coil springs 248 are interposed, these springs operating to exert a yielding force upwardly against the link 240 which latter operates through an opening 249 in the base member 67. The upper end of the link 240 terminates in a slotted head 250 provided with a stud 245 and containing an elongated slot 251 through which the shaft 135 extends, the stud 245 being provided with a roller 252 which is held at all times, under 90 the action of the springs 248, against the periphery of a cam 253 fixed on the shaft 135. The auxiliary plunger rods 225 depend from a cross-member 254 provided on the lower end of a vertically reciprocable 95 bar 255 movable in guides 256 on the front plate 133 of the housing 68, the mechanism for reciprocating the plunger rods 225 comprising a lever 257 mounted on the forward 100 end of a shaft 258 journaled in the housing 68, the outer end of this lever containing an elongated slot 259 into which a pin 260 on the bar 255 extends. The shaft 258 is provided, between its ends, with an arm 260 105 (Fig. 4) to the outer end of which a coil spring 261 fastened to the housing 68 is connected, this spring tending to rotate the shaft 258 in a direction to raise the plunger rods 225. The rear end of the shaft 258 is provided with an arm 262 carrying a roller 263 110 which bears at all times against a box cam 263^a rigidly secured to the shaft 135 (Figs. 4 and 14).

The drive of the machine is effected 115 through the medium of a pulley 264 fixed on a shaft 265 journaled in the frame of the machine, this pulley being shown as driven by a belt 266 from a motor 267. The shaft is provided with a pinion 268 which meshes with a gear 269 rotatably mounted 120 on the shaft 58. A clutch, represented generally at 271 and of a common type having a sliding key arrangement and operating when moved to a certain position to cause the gear 269 to be clutched to the shaft 58 125

130

throughout a single complete revolution of this shaft, and thereupon automatically disengage the gear 269 from this shaft, is interposed between this gear and shaft, and 5 the means for conditioning the clutch 271, as stated, comprises a reciprocable rod 272 encircling the shaft 58, at a slotted portion 273 thereof and guidingly confined between its ends in a bearing 274 on the frame of 10 the machine, a coil spring 275 being confined between a stop 276 on this bar and the bearing 274 and tending to shift this rod to the left in Fig. 6. The forward end of the rod 272, which is provided with a 15 stop 277 adapted to engage the bearing 274 in the unclutched position of the clutch controlling the gear 269, is pivotally connected at 272^a with one end of a rod 272^b, the outer end of which is pivotally connected with the 20 lower end of an arm 278 depending from a shaft 279 journaled in bearings 280 depending from the top plate 30 of the frame, this shaft also having an arm 281 pivotally connected at its outer end with the upper 25 end of a link 282 pivotally connected, at 283, with a treadle 284 pivotally connected at its rear end, at 285, with depending brackets 286 on the frame of the machine.

The arrangement of the parts is such that 30 when the operator depresses the treadle 284 it effects a conditioning of the clutch 271 for causing the shaft 58 to make a complete revolution and thereupon automatically stop.

35 Power is transmitted from the shaft 58 to the shaft 135 by any suitable means, as, for example, by the sprocket and belt connection shown which comprises a sprocket chain 287 passing over sprockets 288 and 289 fixed respectively on the shafts 135 and 58.

I desire to employ in connection with the magazine 110, and as means for facilitating the charging of the strips into the grooves 45 of the latter, a separate device which is removable from and replaceable in the machine and, furthermore, is useful in causing the folded portions of the strips (Fig. 15^a) to be tightly compacted, this device being 50 represented, as to the details thereof in Figs. 16 to 19 inclusive and as to its position relative to the other parts of the machine, during the charging of the magazine 110 with the strips, in Figs. 1 and 2 of the drawings.

55 The device just referred to is formed of two separate members 290 and 291 provided on faces thereof with relatively deep grooves 292 and 293 opening through the tops and bottoms of these members, formed by the 60 parallel ribs 294 and 295, respectively. The grooves 292 are substantially of the same width, and spaced apart the same distance, as in the case of the grooves in the magazine 110, and the ribs and grooves of both of the members 290 and 291 are so propor-

tioned and arranged that these members may be assembled to the position shown in Fig. 16 in which the ribs 295 extend into the grooves 292. The member 290 is provided at its opposite sides with laterally-extending handle-equipped studs 296, at its upper edge with a dowel 297 and at its lower edge with dowels 298, the member 290 being also provided at its front face, at opposite ends thereof, with hook-shaped lugs 299 presenting recesses 300 into which eccentrically-disposed pins 301 provided on the end of a shaft 302, which extends across the front face of the member 291 when assembled with the member 290 as shown in Fig. 16, extend, the shaft 302 having a radially-extending handle 303 by which it may be rotated to force the member 291 flatwise toward the member 290 which latter has rigid handles 304 and 305 provided for the purpose of facilitating the handling of the device. The various strips to be charged into the magazine 110 are first inserted into the grooves 292, to flatwise oppose the bottom walls of these grooves and the member 291 thereupon assembled with the member 290 to the position shown in Fig. 16 in which position the strips, which are furnished in folded condition, as shown in Fig. 15^a, become tightly squeezed between the bottoms of the grooves 292 and the opposing edges of the ribs 295. The device of Fig. 16 with the strips thus clamped in place, is then preferably heated in order that the strips shall become set in closely compacted condition, and the device then positioned in the machine as shown in Figs. 1 and 2, in which position the device rests at its lower edge upon the upper edge of the magazine 110, the dowels 298 entering recesses (not shown) in the top portion of the side members 111 of the magazine, to insure the proper positioning of the grooves 292 with the grooves in the magazine. Before thus positioning the device, the operator pushes the sliding supporting structure for the plunger rods 179 upwardly into such a position as to permit the device of Fig. 16 to be applied to position in the machine, as stated, in which position, the plunger rods 179 and guide plate 188^c extend above the magazine 110 a distance slightly greater than the height of the device, the operator, in thus elevating the parts as stated, operating the pawl 199 to a position in which it is out of engagement with the rack 195, by actuating the shaft 214. The operator then lowers the parts elevated as stated, to a position in which the plate 188^c rests upon the top surface of the device of Fig. 16, the dowel 297 entering an opening (not shown) in this plate, and thereupon rotates the shaft 302 in counter-clockwise direction in Fig. 2, to release the clamping engagement 120 of the members 290 and 291 against the 125

strips. The operator then continues to force the plunger rods 179 downwardly and through the plate 188^c (which latter remains at rest), engaging the upper ends of the strips and forcing them into the grooves of the magazine and between the feed rolls 140 and 141, which latter have been preliminarily swung away from each other by the manual operation hereinbefore described. In this position of the parts the strips extend slightly above the upper end of the magazine, permitting the operator to withdraw from the magazine any of the strips which may have been malformed, the observing of the same being made possible by the provision of the transparent front wall 114 of the magazine, and also permit, by manipulation, the proper aligning of the upper ends of the strips, should any thereof happen to project above or below the others. After the positioning of the strips by the plungers 179, as stated, the operator again raises the plunger-supporting mechanism, to its original position, and thereupon lifts the device of Fig. 16 out of the machine, following which, and the manipulating of the strips by hand, as stated, if such is done, the operator, by actuating the lever 148 to the position shown in Fig. 6, conditions the rollers 140 and 141 for gripping the strips between them, whereupon the operator, by oscillating the lever 163, by means of the handle 163^a which rotates the rollers 140 and 141 in feeding direction, forces the strips in the magazine 110 to a position in which their lower edges extend substantially in the plane of the shearing edge of the shearing blade 121, in which position of the strips their upper edges extend slightly below the upper edge of the magazine 110. The strips having been thus positioned, the operator thereupon again draws down the supporting structure for the plunger rods 179 to a position in which the bar 188^c bears against the top surface of the magazine 110 and the plunger rods 179 enter the upper ends of the grooves in the magazine and substantially contact with the upper surfaces of the strips therein, in which position of the parts a pointer 306 on the guiding sleeve 184 extends opposite the graduation 25 on the scale provided on the stationary upright 307 forming a part of the super-structure of the machine, the scale in the form shown, and with the number of graduations shown, being provided where each strip is to be cut into twenty-five sections.

The board 35, the openings 36 in which are to be filled with the strip sections, is preferably assembled with a gauging frame before introduction into the machine, this gauging frame comprising a bar 308 provided at one end with a laterally-extending projection 309 and having slidably mounted thereon a block 310 carrying a clamping device 311 through the medium of which this block may be clamped in any desired position along the bar 308, the bar 308 being applied to one of the edges of the board 35 and clamped at its ends, in position between the projections 309 and the block 310 as shown in Fig. 4. The top 30 of the frame is provided to one side thereof with a positioning strip 312 extending lengthwise of the machine and adapted to form a guide along which the bar 308 slides. The bar 308, preferably provided with the undercut grooves 313, is provided with a pointer-equipped positioning stop device 314 having portions which extend into the undercut grooves 313 adapting this device to be slid along the bar 308 while interlocked therewith. The device 314 is provided at its forward end with an upturned finger 315 positioned to engage the forward edge of the magazine when the board is introduced into the machine to the position shown in Fig. 6, the device 314 also being formed with a pointer 316 overlapping the board 35 and with a tightening screw 317 adapting the device 314 to be rigidly secured to the bar 308 in adjusted position thereon. The parts just described are so proportioned and arranged that when the board is assembled with the gauging device 308 to the position shown in Fig. 4 and the device 314 is adjusted along the bar 308 to a position in which the pointer 316 is in direct line with the row of holes 36 in the board 35 which it is desired be first filled, and the assembled board and gauging device is introduced into the machine to the position shown in Fig. 4, the row of holes first to be filled and extending opposite the pointer 316 will extend directly below the plunger rods 225. In introducing the board into the machine, as stated, the operator preliminarily lifts the presser roller 62, as hereinafter described, so that it will not interfere with the ready introduction of the board into the machine. In the positioning of the board in the machine as stated, the uppermost pins 42 of the feed rolls 39 project upwardly into the holes 36^a in the board directly above them. In the normal, inoperative position of the machine the pawl 85 is held out of engagement with the ratchet 84 by the lug 92^a thereby permitting the drums 39 to be freely rotated in either direction to insure alignment of certain of the pins 42 thereon with holes in the board for the purpose of causing the row of holes in the board to be filled to extend into proper position in the machine, it being preferred that, before the desired final positioning of the board in the machine, the operator re-position the presser roller 62 to cause it to yieldingly bear against the upper surface of the board. The machine now being ready to operate, the operator to fill the first line of holes 36, in the

board, to be filled, momentarily presses down on the treadle 284, with the result of causing the shaft 58 to rotate one single revolution, but inasmuch as in the particular machine illustrated the feeding means for the board is one of the first mechanisms to operate, the operator, by actuating the lever 99, renders the pawl 85 inoperative during the first revolution of the shaft 58 in order that the first row of holes 36 may be filled. This results first in moving the carrier 216 forwardly to the position shown in Fig. 7 and thereafter pulling down the pawl 199 while in engagement with a tooth of the rack 196, thereby lowering the plunger rods 179 a distance of one tooth and simultaneously therewith causing the rollers 140 and 141 to rotate at the same surface speed as the speed of movement of the rods 179 in feeding direction against the strips therebetween, which lowers the strips a distance equal to the length of the strip sections to be cut therefrom for introduction into the holes in the board, the lower ends of these strips entering the openings 223 and between the lower ends of the flexible strips 224 of the carrier 216. Thereupon the mechanism for actuating the shearing bar 121 is actuated with the result of shearing from the main body portions of the strips the portions of the strips extending beneath the plane of the cutting edge of the shearing element 121. The mechanism for moving the carrier 216 rearwardly into a position in which the openings therein filled with the strip sections extend directly beneath the plunger rods 225 and in alignment with the first row of holes 36 in the board and the carrier is lowered to a position in which the lower ends of its spring fingers 224 extend part way into the particular row of holes 36 to be charged with the strip sections in the carrier, is then brought into operation and, while these spring fingers are in the holes in the board, the plunger rods 225 descend, forcing the strip sections in the carrier into the holes 36 in the board directly beneath them, the carrier 216 starting to rise before the plunger rods 225 complete their downward movement and completing its rising movement, to a position in which the lower extremities of the fingers 224 extend above the plane of the board, by the time the plungers 225 have completed their downward movement, these plungers thereafter rising to the position shown in Fig. 8. The operations above stated are effected in the complete single rotation of the shaft 58, at the conclusion of which single rotation, the machine comes to rest. With each depression of the treadle, the cycle of operations hereinbefore described is repeated, it being understood that in each rotation of the shaft 58 after the first thereof, the operator having released his grip on the lever 99, the board is fed a distance equal to the distance

between adjacent rows of holes 36 therein, or a multiple of such distance depending on the setting of the feeding mechanism as hereinbefore explained. Thus where the magazine is charged with strips which are to be cut into, say twenty-five sections, for filling twenty-five rows of holes 36 in the board, the operator operates the treadle twenty-five times, each cycle of operations filling one row of holes. Where the feeding mechanism for the board is so adjusted that every other row of holes 36 or every third row of holes 36 is filled, the operator, after filling the last row of the series of holes then being filled, will re-position the board in the machine for filling the remaining rows of holes and alternating with the filled holes, assuming that every other one of the rows of holes in the board were filled in the first passage of the board through the machine; and, in the event that every third one of the rows of holes was filled, in the first passage of the board through the machine, the operator adjusts the board in the machine to fill certain of the remaining unfilled holes, and after these have been filled, by again positioning the board in the machine, to fill the remaining rows of holes.

The feature of providing both the plungers 179 and the feed rolls 140 and 141, the plungers operating to push the strips through the magazine and the feed rolls operating to exert a pulling action thereon during the feeding of the strips while of relatively long lengths, is of advantage as thereby the buckling of the strips, which oftentimes causes the strips to become wedged in the magazine or otherwise resistant to being fed therethrough by a pushing action against a long strip, is overcome and the strips are uniformly and evenly fed through the magazine.

Furthermore the feature of providing the spring fingers 224 is also of great advantage especially where the boards, the holes in which are to be filled, are warped or otherwise distorted, inasmuch as even should the holes to be filled not extend in true alignment with the openings 223 in the carrier 216, the fingers 224 will deflect laterally and present ways along which the strip-sections move into the holes to be filled, inclined to the plane of these holes.

From the foregoing it will be noted that the strip sections are caused to be positioned in the carrier 216 from which they are pushed into the holes 36, in the board, to be filled; and while the magazine 110 is shown as extending at a right angle to the path of movement of the board, this is not necessary in practicing my invention, as the magazine may be otherwise disposed. Thus as shown in Figs. 20 to 22, inclusive, which illustrate another embodiment of my invention, the magazine is disposed at an oblique angle to

the board, this machine differing from the structure of the preceding figures, mainly as regards the intermediate carrier for the strip sections and its actuating mechanism.

- 5 Referring to the machine of Figs. 20 to 25 inclusive, the main frame of the machine is represented at 400, and the top plate thereof, and upon which the board 35 to be filled rests, and along which it is movable, at 401. 10 The main drive shaft of the machine represented at 402 and corresponding with the shaft 58 and which may be driven as explained of the latter, co-operates with mechanism, as described of the shaft 58, for 15 actuating the board-feeding rolls 403 (corresponding with the feed rolls 39), this board-feeding mechanism being of the same construction, and operating in the same manner, as in the case of the machine of 20 the preceding figures, whereby the board 35 is caused to be moved toward the front of the machine by a step-by-step movement.

In the particular machine now being described, the magazine for the strips, this magazine being represented at 404 and corresponding with the magazine 110, instead of extending at a right angle to the plane in which the board 35 moves, extends at an oblique angle thereto, and the pusher rods, 25 represented at 405, and corresponding with the pusher rods 179, also extend at the same oblique angle. In this construction the lower, socketed, supporting brackets 406, corresponding with the brackets 107, are 30 supported on the front side 407 of a casing 408 mounted on the table top 401 as explained of the housing 68. The brackets 406 receive the outwardly projecting studs 409 on the ends of the magazine 404, the 35 upper outwardly projecting studs 410 on the ends of the magazine co-operating with latches 411 and provided for the same purpose as the rock levers 117, the latches 411 being in the form of T-levers fulcrumed at 40 their angles on the wall of the housing 408, as indicated at 412. One arm 413 of each lever 411 co-operates with a spring 414 which yieldingly rocks the lever controlled thereby in counter-clockwise direction in 45 Fig. 22 and the other arms 415 of the levers 411 extend into the path of movement of lugs 416 provided on a shaft 417 journalled in the housing 408 and provided with a 50 crank handle 418 by means of which the operator may rotate the shaft 417 to disengage the latches from the studs 410 in the removing and replacing of magazines. The magazine 404 is provided with feed rolls for the strips and also with shearing mechanism, 55 as explained of the magazine 110, these feed rolls and the shearing mechanism being operated in the same manner as in the previously described construction, but by slightly different mechanism, the mechanism by 60 which such operations are effected being

slightly different owing to the change in the angle to which the magazine extends relative to the plane in which the board is fed. The feed rolls referred to are carried by the shafts 419 and 420 which are driven in opposite directions for feeding from a clutch device 421 geared to the shafts 419 and 420 as in the preceding construction, the clutch device 421 corresponding with the clutch device 160 of the preceding figures, its oscillating actuating member being represented at 422. The means for actuating the member 422 comprises a plunger 423 slidably mounted in the housing 408. The forward end of this plunger abuts the oscillating member 422 and with each movement of the plunger 423 to the left in Fig. 22 against the action of a retracting coil spring 424, surrounding the plunger 423 and interposed between a wall of the housing 408 and a pin 425 on the plunger, actuates the clutch 421 in a direction to rotate the feed rolls. The mechanism for actuating the plungers 423 simultaneously with the lowering of the plunger rods 405, comprises fingers 426 mounted on a shaft 427 journalled in the housing 408, this shaft being provided with a depending arm 428 carrying a roller 429, which bears against a cam 430 mounted on a shaft 431 corresponding with the shaft 135 of the construction of the preceding figures, it being understood that the plunger 423 reciprocates with each rotation of the shaft 431. 100 The machine is also equipped with a shearing member as explained of the construction of the preceding figures operated in the same manner by mechanism which differs slightly from that of the last referred to machine, by virtue of the change in position of the magazine. The arms of the shearing-blade-operating mechanism through the medium of which the blade is actuated, and corresponding to the arms 130 of the machine of the preceding figures, are 105 represented at 432, the operative connections between these arms and the shearing blade being the same as in the machine of the preceding figures. In the particular construction now being described, the arms 432 under the tension of the springs 433 oppose the forward ends of upwardly and forwardly inclined plungers 434, which slide in the forward plate of the housing 408, these plungers being located at opposite sides of the magazine. The rear ends of the plungers 434 operatively engage with the lower ends of rock levers 435 pivotally supported between their ends, at 436, on the housing 408, the upper ends of these levers being pivotally connected, at 439, with the forward ends of the bars 440 each of which contains an elongated slot, as indicated of the one shown in Fig. 22, at 441, the shaft 431 extending through these slots. The members 110 115 120 125 130

440 are provided with rollers 442 and 443 respectively which bear against the peripheries of cams 444 and 445 respectively, secured to the shaft 431. The cams 444 and 445 correspond, respectively, with the cams 136 and 137 of the machine of the preceding figures and, in conjunction with the crank-pin connection of the shearing blade with the operating mechanism therefor, as explained of the machine of the preceding figures, causes the shearing blade to operate the same as in this last referred to machine.

The plunger rods 405 of the machine now being described are connected with the frame-like structure, of the same general construction as the machine of the preceding figures and comprising upper and lower sleeves 447 and 448 surrounding, and slideable up and down on, parallel rods 449 rising from the housing 408, in a rearwardly inclined direction, these sleeves being connected together by rods 450, upon which the bar structure 451 and corresponding with the member 188^a of the machine of the preceding figures, is slideable. The frame for the plunger rods 405, which is substantially counterbalanced by the counterweight 451^a connected by a cable 452 with the frame referred to, carries a rack bar 453, and corresponding with the bar 195, with which bar a pawl 454 co-operates to intermittently lower the plunger rods 405. The pawl 454 is pivotally connected at its lower end, as indicated at 455, to the forward end of a lever 456 pivotally supported at 457 on the upper end of a bracket 458 secured to the base of the housing 408, the rear end of the lever 456 being provided with a roller 459 bearing against the periphery of a cam 460 rigid on the shaft 431. A spring 461 secured at one end to the lever 456 bears yielding against the pawl 454 to cause the latter to bear against the rack teeth 453 at all times, it being understood that each time the shaft 431 makes a complete rotation, one complete reciprocation of the pawl 454, and consequently the lowering of the plunger rods 405, a distance equal to the length of one of the teeth of the rack 453, is effected.

The machine now being described also employs a roller, represented at 462 corresponding in function to the roller 62 of the preceding figures, this roller journalled in the forward ends of levers 463, one at each side of the machine, pivotally supported between their ends as indicated at 464 of the one shown in Fig. 22, and bearing, under the action of springs 465 against the lower ends of plungers 466 slideable up and down in the base of the housing 408, the upper surfaces of these plungers engaging the peripheries of cams 467 on a shaft 468 journalled in the sides of the housing and provided with a crank handle 469 through the medium of which it is adapted to be manu-

ally partially rotated to lift the roller 462 for the purpose explained in connection with the roller 62.

Referring now to the carrier into which the strips are forced from the magazine, through the medium of the plunger rods 405 and the feed rolls at the lower end of the magazine and from which carrier the severed strip sections are introduced into the holes 36 in the board, and to the operating mechanism therefor; this mechanism comprises the bar member represented at 470 which extends transversely of the machine and contains, in its portion 471, a series of openings corresponding with the strip-section-receiving openings of the carrier of the preceding figures, and which are spaced the same distance apart as the grooves in the magazine and from which openings the pairs of spring fingers 472, like the fingers 224, depend. The extremities of the member 470 terminate in trunnions 473, the portions of the member 470 adjacent the trunnions, and represented at 474, having flat opposed sides at which portions the member 470 extends into elongated slots 475, forming guides, in guide bars 476 rigidly secured to the inner ends of shafts 477 journaled in surrounding sleeves 478 which, in turn, are journaled in uprights 479 rising from the bed 401 of the machine and rigidly secured thereto, the uprights 479 containing vertically elongated slots 480, forming guides for a purpose hereinafter described. The outer ends of the shafts 477 are each provided with a crank 481, the crank-pins 482 of which are connected with the forward ends of rods 483, respectively located at opposite sides of the machine and each containing in its rear end an elongated slot 484 through which the shaft 402 extends and upon which latter these bars are slideable lengthwise, each of these bars being provided on a face thereof with a roller 485, these rollers, under the action of coil springs 486 connected with these bars and with the stationary frame of the machine, bearing against the peripheries of cams 487 rigidly secured to the shaft 402, these cams, in a single rotation of the shaft 402, producing one complete oscillation of the shaft 477, it being understood from the foregoing that the mechanism just described will operate to swing the member 470 and the guide bar 476 engaged thereby from a position in which it extends at a right angle to the plane of the board, the position occupied by these parts in the normal position of the machine, to a position in which it extends in rearwardly inclined position in which it registers with the magazine as shown generally in Fig. 22. In the rearwardly inclined position referred to, the member 470 is adapted to receive the lower ends of the strips in the magazine, when the plunger

rods 405 are depressed, following which operation the shearing mechanism for severing these portions of the strips from the remaining portions thereof, in the magazine, are 5 operated, and when the member 470 is swung to the position in Fig. 24, as stated, the strip sections are thereby carried into a position in which they extend substantially at a right angle to the plane of the board and are 10 in direct vertical alignment with the holes 36, in the board, to be filled. It is, however, desirable that the member 470 be lowered relative to the position thereof shown in Fig. 22, previous to the forcing of the strip 15 sections from the carrier into the holes 36, and this is effected in the particular construction now being described, by locating the trunnions 473 in the irregular shaped slots 488 contained in plates 489 rigidly secured to the sleeves 478. The shape of the 20 slots 488 is such, as shown, that when these plates are rotated in clockwise direction in Fig. 22 from the position therein shown, to the position shown in Fig. 24, the member 25 470 will be lowered in the guide members 476 into a position in which the fingers 472 project slightly into the openings 36, in the board, to be filled, the shape of these slots however being such that practically the entire 30 lowering movement of the member 470 occurs during the latter part of the movement of the guide members 476 from the position shown in Fig. 22 to the position shown in Fig. 24, so that these fingers enter the 35 holes 36 practically in a vertical direction. The means for actuating the slotted plates 489 comprise pinions 490 secured to the outer ends of the sleeves 478, these pinions meshing with rack-bars 491 guided at their 40 forward ends on bearing blocks 492 secured to the top 401 of the machine and located at opposite sides of the machine, the rear ends of the rack-bars 491 containing elongated slots 493 through which the shaft 402 45 extends and relative to which latter these rack-bars are slideable lengthwise. The rack-bars 491 are provided on their faces with rollers 494 which bear, under the action of coil springs 495 each rigidly held at 50 one end to the machine and connected at its opposite end with one of the rack-bars with which it co-operates, against the peripheries of cams 496 rigidly secured to the shaft 402, whereby each rotation of the shaft 402 effects 55 a complete reciprocation of the rack-bars 491. It may be here explained that the cams 496 are so shaped and arranged, as shown, that immediately following the movement of the members 470 from the inclined position shown in Fig. 22, to the vertical position shown in Fig. 24, the fingers are projected downwardly into the holes 36 beneath them and almost immediately thereafter rise slightly out of the holes, but not 60 until after the plungers cooperating there-

with and hereinafter described have lowered sufficiently to enter the lower ends of the strip-sections into the holes 36.

The strip-sections, carried by the member 470, and to be charged into the holes in the board, are operated on, to effect this transfer, by a series of plunger rods represented at 498, spaced apart the same distance as the strip-receiving holes in the member 471 and aligning therewith, these plunger rods being 70 carried by a member 499, which extends at its end portions into the vertically disposed guide slots 480 of the member 479 and in which the member 499 is vertically slideable, the extremities of the member 499 being in 75 the form of pivot-forming projections 500, as shown of one end of the member 499 in Fig. 23. The pivoting projections 500 engage the upper ends of links 501 arranged at opposite sides of the machine and containing slots 502 through which the outer ends of the shafts 477 and the sleeves 478, extend, the lower ends of these links being connected by the pivot pin and slot connections shown at 503, with the forward ends of levers 504 80 fulcrumed between their ends, as represented at 505, to the top 401 of the machine at opposite sides thereof, the levers 504 which engage with coil springs 506 operating 85 to yieldingly turn them in clockwise direction in Fig. 24 and normally hold the plunger rods 498 in elevated position in which they are out of the path of movement of the member 470 when the latter is actuated as hereinbefore described, and provided 90 at their rear ends with rollers 507 which, under the action of the springs just referred to, bear against the periphery of cams 508 rigidly secured to the shaft 402, it being understood that each complete rotation 95 of the shaft 402 operates to effect a complete vertical reciprocation of the plunger rods 498, the parts being so constructed and arranged that these rods will not be brought to a position in which they enter the openings in the member 470 occupied by the strip sections, until the member 470 has been 100 lowered to vertical position and lowered to extend at its fingers 472 slightly into the holes 36 beneath them. The arrangement of the various parts described is also such that, as shown, the member 470 will rise, to a position intermediate its extreme lower position and its extreme upper position, in which intermediate position the fingers 105 472 will extend above the upper surface of the board following the lowering of these fingers into the holes 36, before the plunger rods 498 have completed their downward movement, this intermediate position being 110 shown in Figs. 23 and 24, the strip sections being shown in Fig. 23 as almost completely entered into the openings 36.

In the machine illustrated the shaft 431, 115 which is operated at the same speed as the 120

shaft 402, is driven from the latter, as through the medium of a sprocket chain 509 engaging sprockets 510 and 511 on the shafts 431 and 402, respectively.

5 The general cycle of operations of this machine are the same as those of the machine of the preceding figures and detailed description thereof therefore appears to be unnecessary.

10 While I have illustrated and described certain particular embodiments of my invention, I do not wish to be understood as intending to limit it thereto as the same may be variously modified and altered without departing from the spirit of my invention.

15 What I claim as new, and desire to secure by Letters Patent, is:

1. In a machine of the character set forth, the combination of a magazine for the strips in folded condition, severing means for cutting the strips into short lengths, means for supporting a board the holes in which are to be charged with the strip sections, a member for receiving portions of the strips, means 20 for advancing the strips in said magazine and into said member said member being movable into a position in which the strip sections therein extend substantially at a right angle to said board and in line with holes therein to be filled, means for actuating said member, and means for discharging the strip sections from said member into the holes aligning therewith.

2. In a machine for the character set forth, 25 the combination of a magazine for the strips in folded condition, severing means for cutting the strips into short lengths, means for supporting a board the holes in which are to be charged with the strip sections, a member for receiving portions of the strips, means for advancing the strips in said magazine and into said member, said member being movable in a direction crosswise of said magazine into a position in which the strip sections therein extend substantially at a right angle to said board and in line with holes therein to be filled, means for actuating said member, and means for discharging the strip sections from said member into the holes aligning therewith.

3. In a machine of the character set forth, 30 the combination of a magazine for the strips in folded condition, severing means for cutting the strips into short lengths, means for supporting a board the holes in which are to be charged with the strip sections, a member for receiving portions of the strips, means for advancing the strips in said magazine and into said member, said member and said magazine being relatively movable, and means for discharging the strip sections from said member into holes in the board aligning therewith.

4. In a machine of the character set forth, 35 the combination of a magazine for the strips,

severing means for the strips, means for supporting a board the holes in which are to be charged with strip sections, a member for receiving portions of the strips, means for advancing the strips in said magazine and into said member, said member being movable downwardly from a position in which it aligns with said magazine into a position in which the strip sections therein extend substantially at a right angle to 40 said board and in line with holes therein to be filled, means for actuating said member, and means for discharging the strip sections from said member into the holes aligning therewith.

5. In a machine of the character set forth, the combination of a magazine for the strips in folded condition, severing means for cutting the strips into short lengths, means for supporting a board the holes in which are to be charged with the strip sections, a member for receiving portions of the strips, means for advancing the strips in said magazine and into said member, said member being movable into a position in which the strip sections therein extend substantially at a right angle to said board and in line with holes therein to be filled, means for actuating said member, and plungers for discharging the strip sections from said member into the holes aligning therewith.

6. In a machine of the character set forth, the combination of a magazine for the strips, severing means for the strips, means for supporting a board the holes in which are to be charged with strip sections, a member for receiving portions of the strips, means for advancing the strips in said magazine and into said member, said member and magazine being relatively movable and said member having depending fingers at the portions thereof receiving said strip sections and being movable downwardly from a position in which it aligns with said magazine into a position in which it extends substantially at a right angle to said board and in line with holes therein to be filled and in which position said fingers extend into said holes, and means for discharging the strip sections from said members into the holes aligning therewith.

7. In a machine of the character set forth, the combination of a magazine for the strips, severing means for the strips, means for supporting a board the holes in which are to be charged with strip sections, a member for receiving portions of the strips, means for advancing the strips in said magazine and into said member, said member and magazine being relatively movable and said member having depending fingers at the portions thereof receiving said strip sections and being movable downwardly from a position in which it aligns with said magazine into a position in which it extends sub-

stantially at a right angle to said board and in line with holes therein to be filled and in which position said fingers extend into said holes, and means for discharging the 5 strip sections from said member into the holes aligning therewith, said means for actuating said member being in the form of plungers and said last-named means and said member-actuating means being so timed in 10 their operation that said fingers enter said holes before said plungers begin the feeding of said strip sections and said fingers begin their withdrawal movement from said holes before said plungers begin their retracting 15 movement.

8. In a machine of the character set forth, the combination of a magazine for the strips, severing means for the strips, means for supporting a board the holes in which are 20 to be charged with strip sections, a member for receiving portions of the strips, means for advancing the strips in said magazine and into said member, said member and magazine being relatively movable and 25 said member having depending fingers at the portions thereof receiving said strip sections and being movable downwardly from a position in which it aligns with said magazine into a position in which it extends substantially at a right angle to said board 30 and in line with holes therein to be filled and in which position said fingers extend into said holes, said fingers being spring fingers and arranged to flex in the passage 35 of said strip sections therebetween, and means for discharging the strip sections from said member into the holes aligning therewith.

9. In a machine of the character set forth, 40 the combination of a magazine for the strips, severing means for the strips, means for supporting a board the holes in which are to be charged with strip sections, a member located below said magazine for receiving portions of the strips, means for advancing the strips in said magazine and into said member, said member being movable, in the general direction of the plane 45 of the board, from a position in which it extends in line with said magazine, to a 50 position in which it extends to one side of the magazine, and in lowered position in which the strip sections therein extend substantially at a right angle to the plane of 55 the board and closely adjacent, and in line with, the holes therein to be filled, means for actuating said member, and means for discharging the strip sections from said member into the holes aligning therewith.

10. In a machine of the character set forth, 60 the combination of a magazine for the strips, severing means for the strips, means for supporting a board the holes in which are to be charged with strip sections, a member located below said magazine for

receiving portions of the strips, means for advancing the strips in said magazine and into said member, said member being movable, in the general direction of the plane of the board, from a position in which it extends in line with said magazine, to a position in which it extends to one side of the magazine, and in lowered position in which the strip sections therein extend substantially at a right angle to the plane of the 70 board and closely adjacent, and in line with, the holes therein to be filled, said member being provided with depending portions at the strip-section-receiving openings therein, which extend, in the last-referred-to position of said member, into said holes, means for actuating said member, and means for discharging the strip sections from said member into the holes aligning therewith. 80

11. In a machine of the character set forth, 85 the combination of a magazine for strips, presenting grooves through which the strips are advanced, feed plungers operating against the ends of said strips, and roller feed mechanism engaging said strips 90 beyond said plungers.

12. In a machine of the character set forth, 95 the combination of a supporting member, a removable and replaceable magazine for strips mounted on said supporting member and provided with strip-receiving grooves, means on said supporting member for engaging the ends of said strips and feeding them in the magazine, roller-feed mechanism for engaging the strips beyond 100 said first-named means and comprising rollers and actuating mechanism therefor, said rollers being mounted on said magazine to be removable and replaceable therewith.

13. In a machine of the character set 105 forth, the combination of a supporting member, a removable and replaceable magazine for strips mounted on said supporting member and provided with strip-receiving grooves, means on said supporting member for engaging the ends of said strips and feeding them in the magazine, roller-feed mechanism for engaging the strips beyond 110 said first-named means and comprising rollers and actuating mechanism therefor, said rollers being mounted on said magazine to be removable and replaceable therewith, a portion of said roller-actuating means being likewise mounted on said magazine and movable therewith and the remaining portion mounted on said supporting member. 115

14. In a machine of the character set 120 forth, the combination of a supporting member, a removable and replaceable magazine for strips mounted on said supporting member and provided with strip-receiving grooves, means on said supporting member for engaging the ends of said strips and feeding them in the magazine, roller-feed mechanism for engaging the strips beyond 125 130

said first-named means and comprising rollers and actuating mechanism therefor, said rollers being mounted on said magazine to be removable and replaceable therewith, and being movable toward and away from each other.

15. In a machine of the character set forth, the combination of a supporting member, a magazine for the strips removably mounted on said supporting member, means for feeding the strips through said magazine, a shearing member for the strips carried by said magazine and removable with the latter as a unit, and means for actuating said shearing mechanism.

16. In a machine of the character set forth, the combination of a supporting member, a magazine for the strips removably mounted on said supporting member, means for feeding the strips through said magazine, a shearing member for the strips carried by said magazine and removable with the latter as a unit, and means for actuating said shearing member, portions thereof being carried by said magazine and by said supporting member, respectively, said last-named means comprising rotatably-mounted eccentric devices carried by said magazine and operatively engaging said shearing member.

17. In a machine of the character set forth, the combination of a supporting member, a magazine for the strips removably mounted on said supporting member, means for feeding the strips through said magazine, a shearing member for the strips carried by said magazine and removable with the latter as a unit, and means for actuating said shearing member portions thereof being carried by said magazine and by said supporting member, respectively, said last-named means comprising rotatable eccentric devices carried by said magazine and set at different angles with respect to each other and operatively engaging said shearing member.

18. In a machine of the character set forth, the combination of a supporting member, a magazine for the strips removably mounted on said supporting member, means for feeding the strips through said magazine, a shearing member for the strips carried by said magazine and removable with the latter as a unit, means for actuating said shearing member, portions thereof being carried by said magazine and by said supporting member, respectively, said last-named means comprising rotatably-mounted eccentric devices carried by said magazine and operatively engaging said shearing member, and eccentric projections on said eccentrics and adapted to be engaged, by the portion of said shearing member-operating mechanism mounted on said supporting member.

19. In a machine of the character set forth, the combination of a supporting member, a magazine for the strips removably mounted on said supporting means, feeding means for said strips, a strip-severing element carried by said magazine, and means for actuating said element formed of disconnectable parts certain of which are carried by said supporting member.

20. In a machine of the character set forth, feeding means for the board comprising a rotatable member provided with projections adapted to enter, in succession, holes in the board and by such engagement therewith feed the board, and means for charging the holes in the board as they are moved by said first-named means into alignment, successively, with said last-named means.

21. In a machine of the character set forth, feeding means for a board provided with aligning holes exposed at opposite faces thereof, comprising a rotatable member provided with projections adapted to enter, in succession, the holes exposed at one face of the board and by such engagement therewith feed the board.

22. In a machine of the character set forth, feeding means for the board comprising a rotatable member provided with peripherally-disposed radially-projecting devices slidably mounted in said member, and means yieldingly urging said projections outwardly.

23. In a machine of the character set forth, the combination of feeding means for the board comprising a rotatable member provided peripherally with inwardly-yielding projections through the medium of which the board is fed, means for driving said member, means for inserting strip sections into holes in the board, and means operating during the strip-inserting operation to hold those of said projections which are in engagement with the board, against yielding.

24. In a machine of the character set forth, the combination of feeding means for the board comprising a rotatable member provided peripherally with projections adapted to enter in succession holes in the board, and by such engagement therewith feed the board, said projections being yieldable inwardly, means, operating in timed relation to said feeding means, for introducing strip sections into holes in the board to be filled, and means, operating intermittently, to hold said projections against yielding while in engagement with the board, said last-named means being out of a position for preventing yielding of said projections, in the normal position of the parts of the machine.

25. In a machine of the character set forth, feeding means for the board comprising a rotatable member provided periph-

erally with yielding projections adapted to enter, in succession, holes in the board and by such engagement feed the board, and means operating to prevent yielding of said 5 projections as they successively reach a certain position in the rotation of said member.

26. In a machine of the character set forth, the combination of means for inserting strip sections into holes in the board, 10 feeding means for the board comprising a rotatable member provided peripherally with projections adapted to enter, in succession, holes in the board and by such engagement therewith feed the board into a position 15 to receive strip sections, means for rotating said rotatable member, said rotatable member at the conclusion of each feeding movement being adapted to slightly rotate, and means for insuring alignment of the 20 holes to be filled, relative to said first-named means comprising a member having a fixed position on the machine and adapted to engage one of said projections.

27. In a machine of the character set 25 forth, the combination of means for inserting strip sections into holes in the board, feeding means for the board comprising a rotatable member provided peripherally with projections adapted to enter, in succession, holes in the board and by such engagement therewith feed the board into a position to receive strip sections, means for rotating said rotatable member, said rotatable member at the conclusion of each feeding 30 movement being adapted to slightly rotate, said projections presenting tapered centering surfaces, and means having a fixed position on the machine cooperating with said inclined surfaces for centering the 35 holes to be filled, relative to said first-named means.

28. A magazine for the purpose set forth, comprising a member presenting a series of grooves in a face thereof, and a plate located at the open sides of said grooves and 40 extending in spaced relation, but closely adjacent, to the grooved face of said member.

29. In a machine of the character set forth, the combination of a magazine for 45 the strips provided with grooves open at opposite ends, feeding means for advancing the strips in said magazine movable into and out of a position in which they enter said grooves, and a removable and replaceable strip-holding device containing grooves open at its opposite ends and adapted to be positioned between said magazine and said means for aligning its grooves with the grooves in said magazine and with said 50 feeding means.

30. In a machine of the character set forth, the combination of a magazine for the strips provided with grooves open at opposite ends, and feeding means for advancing the strips in said magazine, said 55

feeding means comprising a series of plungers adapted to enter said grooves, a guide member for said plungers and through which the latter operate, and operative connections between said plungers and said 70 guide member, whereby said guide member is movable with said plungers in moving the latter away from said magazine, said guide member being held against movement in the movement of said plungers in feeding the 75 strips through the magazine.

31. A machine of the character set forth, comprising means for inserting strip sections into holes in the board, and means for intermittently feeding the board for causing the holes therein to align with said first-named means, adjustable for varying the length of the feeding movement.

32. A crimped strip-receiving device 85 formed of members each provided on its face with a series of ribs spaced apart, the ribs on one of said members presenting strip-receiving grooves open at opposite ends adapted to receive the ribs of the other of said members, and means releasably securing said members together.

33. In a machine of the character set forth, the combination of a magazine for the strips, severing means for the strips, means for supporting a board the holes in which 95 are to be charged with strip sections, a member containing openings for the insertion therein of portions of the strips, means for advancing the strips in said magazine and into said member, said member being movable into a position in which the strip sections therein extend substantially at a right angle to said board and in line with holes therein to be filled, means for actuating said member, and means engaging those ends of 100 the strips opposite those which first enter said openings, for discharging the strip sections from said member into the holes aligning therewith.

34. In a machine of the character set forth, the combination of a magazine for the strips, severing means for the strips, means for supporting a board the holes in which are to be charged with strip sections, a member for receiving portions of the strips, means for simultaneously advancing the strips in said magazine and into said member, said member being movable into a position in which the strip sections therein extend substantially at a right angle to said 115 board and in line with holes therein to be filled, means for actuating said member, and means for discharging the strip sections from said member into the holes aligning therewith.

35. In a machine of the character set forth, the combination of a magazine for the strips, severing means for the strips, means for supporting a board the holes in which 120 are to be charged with the strip sections, a 125

member for receiving portions of the strips, means for simultaneously advancing the strips in said magazine and into said member, said member and said magazine being relatively movable, and means for discharging the strip sections from said member into holes in the board aligning therewith.

36. In a machine of the character set forth, the combination of a magazine for the strips, severing means for the strips, means for supporting a board the holes in which are to be charged with strip sections, a member for receiving portions of the strips, means for advancing the strips in said magazine and into said member said member being movable into a position in which the strip sections therein extend substantially at a right angle to said board and in line with holes therein to be filled, means for actuating said member, plungers adapted to engage the strip sections in said member and in the condition in which said strips were introduced into said member and operating when actuated to force said strip sections from said member into the

holes aligning therewith, and means for actuating said plungers.

37. In a machine of the character set forth, the combination of a magazine for the strips, severing means for the strips, means for supporting a board the holes in which are to be charged with strip sections, a member located below said magazine for receiving portions of the strips, means for advancing the strips in said magazine and into said member, said member being movable, in the general direction of the plane of the board, from a position in which it extends in line with said magazine, to a position in which it extends to one side of the magazine and in which position the strip sections therein extend substantially at a right angle to the plane of the board and closely adjacent, and in line with, the holes therein to be filled, means for actuating said member, and means for discharging the strip sections from said member into the holes aligning therewith.

WILLIAM P. STRICKLAND.
